Victor J. Evans

ATTORNEY

UNITED STATES PATENT OFFICE.

FLORENCE G. MARK, OF SAN DIEGO, CALIFORNIA.

SANITARY GARMENT.

Application filed July 14, 1926. Serial No. 122,420.

This invention relates to improvements in sanitary garments and has for its primary object the provision of a means for keeping a sanitary napkin in a flat condition when in an applied position upon a wearer.

Another object of the invention resides in a sanitary garment adapted to be worn about the waist of a wearer, and which supports a sanitary napkin in a manner, as not to be noticeable from the rear of the wearer when worn beneath thin outer clothing.

A further object of the invention aims to provide a sanitary garment which includes a waterproof sling for the reception of a sanitary napkin to prevent soiling of the undergarments caused by the penetration of the menstrual flow therethrough, and which also eliminates chaffing of the skin due to dampness.

With these and other objects in view, the invention resides in certain novel construction and combination and arrangement of parts, the essential features of which are hereinafter fully described, are particularly pointed out in the appended claim,—and are illustrated in the accompanying drawing, in which:—

Figure 1 is a perspective view of my improved sanitary garment showing a sanitary napkin in position thereon.

Figure 2 is a rear elevation of the same.

Figure 3 is a vertical sectional view therethrough.

Figure 4 is a detail perspective view showing the sling disconnected with the front flap.

Figure 5 is a horizontal sectional view on the line 5—5 of Figure 4.

Figure 6 is a vertical sectional view on the line 6—6 of Figure 4.

Referring more particularly to the drawing, the reference numeral 10 designates my improved sanitary garment in its entirety, and which includes a waist encircling portion or waist band 11 which is buttonable at one side as at 12. The front of the waist band has a downwardly extending front tab 13, while the back of the waist band has a downwardly extending rear tab 14. The rear tab 14 is sufficiently wide enough to cover the rump of the wearer to impart a flat appearance to the same and is cut to fit the figure so that in turning over in bed, it holds its position with great comfort to the wearer. The waist band and tabs are

cut from a single piece of fabric material but stitched to the free end of the rear tab 14, is a sling 15' of waterproof material having a fabric end 16' which when fastened to the front tab 13 serves as a support and protector for the sanitary napkin 15.

For supporting the napkin in a flat condition upon the sling, I provide a flat bone stay 16 removably supported in loops 17 stitched to the inner face of the back tab 14. The inner sides of the loops are open for the insertion of the ends of the stay but the outer sides are closed to prevent lateral shifting of the same. One end of the sanitary napkin is passed about the stay and folded over the body of the napkin where it is held by a fastening element in the nature of a safety pin 18.

The front end of the napkin 15 and fabric end 16' are passed over a removable flat bone stay 19 mounted in loops 20 provided on the outer face of the front flap 13. Fixedly connected with the stay 19 are one end of ribbons 21, which pass over a flat bone stay 22 loosely mounted in loops 23 directly above the loops 20. After the front end of the napkin is passed over the stay 19, the ribbons 21 are pulled and crossed as shown in Figure 1 of the drawings, which causes the turning of the stay 22 in the loops 23 and brings the same into a plane with the stay 19 as shown in Figure 3 of the drawings. The front end of the napkin and sling are now firmly clamped between the two stays 19 and 21, so that any downward pressure upon the sling will tend to set up a greater clamping action between the stays, it being understood that a removable fastening element in the nature of a safety pin 24 is passed through the ribbons, sling and two thicknesses of the napkin to firmly hold the same.

When it is desired to replace a soiled napkin with a fresh one, the same may be done without removing the garment from the waist of a wearer, as the safety pins are removed and the stays 16 and 19 lifted from their supporting loops, after which the stays may be connected with the ends of the clean napkin and replaced in their supporting loops and the stay 22 brought down into clamping position and fastened as hereinbefore mentioned.

From the foregoing description, it will be seen that the stays serve to keep the ends of the napkin in a spread or flat condition,

thus assuring comfort and neatness to the wearer, as the back tab tends to prevent a bulky appearance at the rear, which might be noticeable when wearing thin clothing.

6 Should it be desired to launder the garment the stays are easily removed and the same laundered in a manner similar to any other garment.

10 While I have described what I deem to be the most desirable embodiment of my invention, it is obvious that many of the details may be varied without in any way departing from the spirit of my invention, and I therefore do not limit myself to the exact 15 details of construction herein set forth nor to anything less than the whole of my invention limited only by the appended claim.

What is claimed as new is:—

15 A sanitary napkin holder comprising a

20 waist encircling band having front and rear tabs and a sling co-extensive with the rear tab, spaced horizontally aligned loops provided on said front tab, a front stay removably supported by said front loops a second 25 set of loops provided on said front flap above the first said loops, a clamping stay loosely and removably supported by said second set of loops, flexible elements fixedly connected to said front stays and adapted to pass over 30 said clamping stay for securing the free end of said sling and one end of a sanitary napkin therebetween upon the securing of the free ends of said flexible elements together and means for securing the opposite end of 35 the napkin to the rear tab.

In testimony whereof I hereby affix my signature.

FLORENCE G. MARK.
